Attorney.

UNITED STATES PATENT OFFICE.

CHARLES T. RASCHICK, OF ST. PAUL, MINNESOTA.

PAD AND PENCIL HOLDER.

1,283,557.

Specification of Letters Patent.

Patented Nov. 5, 1918.

Application filed June 27, 1917. Serial No. 177,422.

To all whom it may concern:

Be it known that I, CHARLES T. RASCHICK, a citizen of the United States, residing at St. Paul, in the county of Ramsey and State 5 of Minnesota, have invented a new and useful Improvement in Pad and Pencil Holders, of which the following is a specification.

This invention relates to a holding device for a pad or series of checks which are 10 bound together in a suitable manner.

The primary object is in providing a device which is formed from a single piece of wire, simple in construction and having a positive pad engaging means, whereby a pad 15 is engaged and firmly held.

A further object is in providing a device which can be disengaged quickly from the stubs of the pad by compressing the sides of the same, to open the pad engaging loop.

20 It is also an object in providing a central circular spring loop by which the holding device can be held to a hook or chain secured to the user of the device and in having spring fingers which are adapted to hold 25 a pencil or other suitable marking element in a convenient position to the holder.

The above objects together with other features will be more clearly defined in the following specifications and claims.

30 In the drawing forming part of this specification:

Figure 1 is a front elevation of the pad holding device secured to a pad, part of which is broken away.

35 Fig. 2 is a side elevation of Fig. 1.

Fig. 3 is a front elevation of the holding device in open position.

Fig. 4 is a perspective of an alternative construction showing the position it would 40 assume in applying it to a pad.

Fig. 5 is a detail of a portion of the alternative construction.

In the drawing, A represents a pad or check holding device which is formed from 45 a single piece of wire 1. The wire 1 is bent so as to form a central circular portion B at the top of the holding device A from which extend downwardly arms 2. The supporting portion B of the device A is 50 shaped like a portion of a coil spring to give an outward spring action to the arms 2. Transverse coils 3 are formed on the lower or free ends of the arms 2 and fingers 4 extend upwardly from the coils 3 so as to form 55 spring engaging fingers for a pencil C or other suitable marking element. The coils 3

give a spring action or resiliency to the fingers 4. The fingers 4 are formed with upper curved ends 5 from which portions 6 extend downwardly, crossing the portions 60 forming the engaging fingers 4 and lying adjacent thereto. The portions 6 have horizontal portions 7 and 8 formed on their lower end which are bent so as to extend inwardly at approximate right angles to the 65 portions 6. The portions 7 and 8 lie adjacent and parallel to each other extending in opposite directions and pass centrally through the loops 3 then being bent to form semicircular portions 9 and 10 which are 70 positioned normally just outside of the spring loops 3. The semicircular portions 9 and 10 have inwardly extending engaging ends 11 and 12 which are adapted to lie approximately parallel to the arms or portions 75 7 and 8.

When the holder A is attached or secured to the pad D, the engaging ends 11 and 12 are adapted to meet at the center of the pad D. The portions 7 and 8 and portions 80 9 and 10, together with the ends 11 and 12, thus form an engaging loop E which is adapted to circumscribe the stub portion of the pad D, which is held by the staple 14.

In engaging the pad C, the portions 11 85 and 12 are adapted to be inserted between the leaves 13 just below the staple 14 as is illustrated in Figs. 1 and 2, thus the engaging or holding device A is adapted to securely hold the pad D against disengagement from the device A without injury to the leaves.

In placing the device A on the pad D, the arms 2 are compressed into the position illustrated in Fig. 3, opening the loop E so that 95 the ends 11 and 12 can be inserted between the leaves 13 of the pad D. The spring loop B forms sufficient pressure to the arms 2 to draw the fingers 11 and 12 together, with possibly a slight assistance by the user. 100 The device A therefore, can be quickly attached or detached from the pad D by compressing the arms 2 to enlarge or open the loop E.

In the alternative construction illustrated 105 in Figs. 4 and 5, the end 11 of the loop E has a hollow tube 15 rigidly secured thereto and the finger or engaging end 12 is adapted to freely slide in the open end 16 of the tube 15. This construction forms an 110 expandable loop E and prevents the disengagement of the end 12 from the tube 15, but

allows it to freely slide therein, so that when the spring arms 2 are compressed together, the loop E will be enlarged so that it can be easily slid or be drawn up between the leaves 13 to the top of the pad D and around the stub end 17 of the pad.

The forming of the device A out of spring wire and from a single piece of material, gives a holder which is light in weight, very durable and practical in use. The pencil holding fingers are used to hold a pencil in a convenient position, so that when a pencil is desired to mark on the checks or leaves 13, it is always handy. The circular supporting portion B is adapted to be engaged by any suitable means such as a belt hook or secured to a chain as may be desired. The arms 2 are positioned far enough apart to allow sufficient compression to open or enlarge the loop E the desired amount.

The holder A is adapted to be disengaged from the pad D by compression of the coiled loop B and engaged to the pad D by expansion of the coil B.

While I have illustrated a particular form and construction of device, I desire to have it understood that I do not wish to confine myself to this particular construction but that the invention can be carried out by other means and applied to uses other than those above set forth within the scope of the following claims:

1. In a device of the class described, a pad and pencil engaging means formed from a single piece of wire comprising a loop which is adapted to be enlarged by the compression of the sides of said device and spring pencil

engaging fingers having spring coils through which said loop extends horizontally.

2. In a device of the class described, having a pad holding means formed from a single piece of wire, means for engaging a pad, said means comprising a horizontal loop which is adapted to be enlarged by compressing the sides of said device, and pencil engaging fingers slidably connected to and projecting from said loop.

3. In a device of the class described, a coiled supporting loop, arms formed with said coil, spring coils formed on the ends of said arms, engaging fingers formed on said spring coils and a pad engaging loop formed horizontally on the ends of said engaging fingers.

4. In a device of the class described comprising, a pad and pencil holder formed from a single piece of wire, a spring coil having arms projecting therefrom, coils formed on the end of said arms, fingers projecting from said coils toward said first coil and an expansible loop formed by the ends of said wire extending from said fingers for the purposes specified.

5. In a device of the class described comprising, a pad and pencil holder formed from a single piece of wire, a spring loop, arms extending from said loop, coil springs formed on the ends of said arms, pencil engaging fingers extending from said coils on the ends of said arms and the ends of said wire extending through said coils on the ends of said arms to form a horizontally extending pad holding loop.

CHARLES T. RASCHICK.
